UNITED STATES PATENT OFFICE.

ROBERT A. ILG, OF CHICAGO, ILLINOIS.

FURNACE.

Application filed October 28, 1926. Serial No. 144,673.

This invention relates to furnaces, having reference more particularly to furnaces of the hot air type used mainly for domestic, church, and school heating.

5 One object of the invention is to provide an improved furnace of the type mentioned capable of being economically constructed almost entirely from the thinnest sheet steel consistent with necessary strength. Another 10 object is to provide a furnace structure embodying improved means for effecting a thorough heat exchange between the exhaust combustion gases and the incoming air. A further object is to provide in such a furnace, 15 improved means for creating a positive and definite flow of air through the air heating passages of the furnace.

Other objects and attendant advantages 20 of the invention will be apparent to persons skilled in the art as the same becomes better understood by reference to the following detailed description, taken in connection with the accompanying drawings wherein I have illustrated a practical and efficient 25 embodiment of the principle of the invention, and in which—

Fig. 1 is a view, partly in side elevation and partly in vertical section, of my improved furnace;

30 Fig. 2 is a front elevation of the same; Fig. 3 is a rear elevation thereof;

Fig. 4 is a vertical longitudinal section taken on the staggered line 4—4 of Fig. 2;

35 Fig. 5 is a vertical transverse section taken on the line 5—5 of Fig. 1;

Fig. 6 is a vertical longitudinal section taken on the staggered line 6—6 of Fig. 2.

Referring to the drawings, 10 designates as an entirety a rectangular sheet-metal 40 housing or casing constituting the outer shell of the furnace structure and equipped with a front wall, the upper portion 11 of which may be of sheet steel or cast iron, while the lower portion 12 is preferably constructed 45 of cast iron to support the fire and draft doors, the operating mechanism of the grate, and the cooling chamber.

Located centrally within and extending lengthwise of the lower portion of the shell 50 or casing 10 is the combustion chamber or fire box 13 of the furnace. This is a relatively narrow long structure, preferably formed with a rounded or dome-shaped top as shown in Fig. 5, with its rear end registering with an opening in the rear wall of 55 the housing normally closed by a door 14

(Fig. 3). On the bottom wall of the combustion chamber are track rails 15 accommodating the wheels of a removable truck 16 on which is mounted a fuel grate 17 of the well-known endless link chain type mounted and supported on front and rear sprocket wheels 19 and 20 respectively. It will be observed, that the grate is not level, as heretofore, but is inclined upwardly from its forward to its rear end, the forward end being but a slight distance above the floor of the ash pit, while its rear end is sufficiently elevated to enable the ashes to be discharged into a removable ash can 21 located beneath the rear end of the grate just inside the rear door 14. This provides ample air space below the grate, and at the same time enables the front door 22 of the combustion chamber to be located at a relatively low point in the front wall of the furnace, thus facilitating firing.

Attached to or cast integral with the lower portion 12 of the front wall and surrounding the opening guarded by the door 22 is a hollow casting 23 adapted to contain water; the lower limb of said casting preferably extending inwardly as shown at 23' above the lower front portion of the grate and serving as a baffle to prevent the body of coal on the latter from clogging between the front wall and the front end of the grate. Water may be supplied to this jacket through a pipe 24; and, where said jacket is used as a hot water heater, the jacket may be additionally provided with an outflow pipe 25 which, with the pipe 24, may be connected into a suitable water tank. In the event that the water in the jacket 23 is used for humidifying the air, the pipe 25 may lead into one of the heated air passages of the furnace at any convenient point. This water jacket also serves to maintain a relatively low temperature of the front wall of the fire chamber, preventing waste of heat through radiation 100 from the latter. The grate is moved to carry the body of burning coal rearwardly and upwardly from time to time as fresh firing is required by a simple foot-operated actuating mechanism herein shown as comprising a gear wheel 26 fast on the shaft of the lower grate sprocket 19, a pinion 27 meshing with said gear wheel and fast on a shaft 28 journaled in the side walls of a suitable casting 29 mounted on the front wall, a ratchet wheel 30 fast on shaft 28, and a pedal lever 31 carrying a pawl 32 engaged with the

ratchet 30. The pedal lever 31 is depressed by the foot to actuate the grate, and is returned to normal elevated position by a pull spring 33. At the bottom of the front wall is a cleanout door 34 in which is mounted the usual draft regulator 35.

The furnace is so constructed as to provide a pair of symmetrical and relatively long passages for the flow of the hot products of combustion to the smoke flue at the top of the furnace, together with a damper-controlled by-pass which may be employed to shorten the outflow passage when firing up, or when a rapid increase in heat is desired; and also with a symmetrical pair of relatively long flow passages for the air to be heated, said air passages being so arranged that the walls of the gas and smoke passages will be efficiently bathed by the air and the heat abstracted therefrom and transmitted to the air.

Within the outer shell or housing 10 and enclosing the major portion of the top and sides of the fire box 13 is a generally rectangular inner sheet-metal hoodlike structure comprising a top wall 36 spaced from the top wall of the housing 10, side walls 37 parallel with and spaced from the side walls of the housing and terminating slightly above the bottom wall of the latter, and a rear wall 38. As best shown in Figs. 4, 5 and 6, the upper portion of this hood is subdivided by suitable partitions to provide draft flues for the products of combustion and also a central vertical flue for the outflow of the heated air. 39 (Fig. 5) designates each of a pair of longitudinal partitions, and 40 and 41 (Fig. 6) a pair of transverse partitions between the longitudinal partitions 39. These partitions, with a portion of the rear wall 38 and the upper portion 11 of the front wall of the outer casing together form a central outflow passage or flue for the heated air communicating with a flue section 42 in the top wall of the casing, to which latter is connected the warm air pipe or pipes leading to the registers. Where artificial circulation of the air is employed, an opening is provided in the upper portion of the rear wall of the outer casing, in which is mounted a frame 43 supporting an electric motor 44 operating a direct driven fan 45, which forces the return air into the space between the outer and inner casings. This air floods the space between the top walls of the casings, flows thence downwardly through the spaces between the side walls, thence upwardly between the side walls of the inner casing and the side walls of the fire box, and thence upwardly through the warm air flue formed by the partitions 39, 40 and 41, the rear wall 38 of the inner casing and the front wall 11 of the outer casing.

Between the longitudinal partitions 39 and extending from the lower edge of the

transverse partition 40 to the rear wall 38 is a horizontal plate 46 (Fig. 6); and similarly positioned between the longitudinal partitions 39 and extending from the upper edge of the transverse partition 41 to the rear wall 38 is a horizontal plate 47. These plates are apertured, and fitted between them is a short by-pass flue section 49. The upper and lower rectangular chambers thus formed communicate through upper and lower ports 50 and 51 respectively with longitudinally extending side flues formed between the longitudinal partitions 39 and the side walls 37 of the hood. The bottoms of these side flues are closed by horizontal plates 52; and the rear bottom and top portions of the space between said side flues are closed by a horizontal plate 53 and the central longitudinal portion of the top wall 36, the former of which is apertured to receive the upper end of a short flue section 55 mounted on and communicating with the combustion chamber 13, while the latter is apertured to receive a smoke discharge flue 56. Attached to the rear wall of each of the side flues between the upper and lower ports 50 and 51 is a longitudinally extending baffle plate 57 that is preferably forwardly and downwardly inclined, as shown in Fig. 4; and within the flue section 49 is a pivoted damper 58 mounted on an operating rod 59 extending through the front wall of the furnace. The outer surfaces of the side walls 37 of the hood are preferably equipped with heat radiating fins 60. On the front wall of the outer casing are cleanout doors 61 normally closing the front ends of the side smoke flues.

Where the fan 45 is employed to create an artificial circulation of the air, it may be located, as shown in Fig. 1, within the cold air return flue 62 which ordinarily communicates with a grating in the floor of the room above the furnace. Fresh air may be permitted to the extent desired by providing on the side of the flue 62 an opening guarded by a pivoted wing valve or damper 63 which may be closed or opened more or less by a rod 64 which may extend to the room above. Automatic regulation of the temperature may, manifestly, be effected by actuating the valve 63 by a thermostat; said valve thus serving not only to admit fresh air when desired, but also, when thermostatically controlled, as an automatic temperature regulator.

The operation and advantages of the described furnace will it is believed be clear from the foregoing description of its structural features.

The cool air, whether forced in by the fan, or flowing in by gravity, flows over the top and sides of the inner shell, below the lower edges of the side walls of the latter, thence upwardly between said side walls

and the sides and top of the fire chamber, and thence upwardly through the relatively large central air flue. With the damper 58 closed, smoke and hot gases of combustion 5 flow from the fire box through the short neck 55, thence through the lower ports 51 into the two side flues below the baffles 57, flowing forwardly beneath the latter, thence around their front ends, thence rearwardly 10 through the upper portions of the side flues, thence through the upper ports 50 into the discharge flue 56. The walls 36 and 37 of the inner shell thus become highly heated through direct contact with the hot gases, 15 and, since these walls are bathed by the air flowing through the furnace, a very efficient heat exchange is effected.

The use of thin sheet-metal in the greater portion of the furnace structure lends itself 20 to economy in production and superior efficiency in heat exchange; and where employed in connection with artificial air circulation, as shown, increases the rapidity with which the rooms served by the furnace 25 can be brought to a desired temperature.

While I have herein shown and described one practical and efficient embodiment of the principle of the invention, it is manifest that minor details of structure and arrangement 30 may be resorted to without departing from the principle of the invention or sacrificing any of the benefits or advantages thereof. Hence, I do not limit the invention to the exact construction shown and described for 35 purposes of illustration, but reserve all such variations, modifications and mechanical equivalents as fall within the spirit and purview of the claims.

I claim:

40 1. In a hot air furnace, the combination of an outer casing having a cold air supply opening in its rear wall, a fire box located in the lower portion of said casing, a hood within said outer casing straddling the top and sides of said fire box with its top, side and rear walls spaced from the corresponding walls of said outer casing to provide downflow air passages communicating at their lower ends with the interior of said hood, smoke flues extending from said fire box through said hood, a warm air discharge flue extending through the top walls of said outer casing and said hood and communicating at its lower end with the space between said hood and fire box, and a fan adapted to force air through the opening in the rear wall of said outer casing.

45 2. In a hot air furnace, the combination of an outer casing having a cold air supply opening in its rear wall, a fire box located in the lower portion of said casing, a hood within said outer casing straddling the top and sides of said fire box with its top, side and rear walls spaced from the corresponding walls of said outer casing to provide

downflow air passages communicating at their lower ends with the interior of said hood, circuitous and direct smoke flues from said fire box formed in said hood, a damper in said direct smoke flue, a warm air discharge flue extending through said hood and outer casing and communicating at its lower end with the space between said hood and fire box, and a fan adapted to force air through the opening in the rear wall of said outer casing.

3. In a hot air furnace, the combination of a rectangular sheet-metal outer casing having a cold air supply opening in its rear wall, a fire box located in and extending full length of the lower portion of said casing, a rectangular sheet-metal hood within said outer casing straddling the top and sides of said fire box with its top, side and rear walls spaced from the corresponding walls of said outer casing to provide downflow air passages communicating at their lower ends with the interior of said hood, circuitous and direct smoke flues from said fire box formed in said hood, a damper in said direct smoke flue having an operating rod extending through a wall of said outer casing, a warm air discharge flue extending through said hood and outer casing and communicating at its lower end with the space between said hood and fire box, and a fan mounted in the opening in the rear wall of said outer casing.

4. In a hot air furnace, the combination of a rectangular sheet-metal outer casing having a cold air supply opening in its rear wall, a fire box located in and extending full length of the lower portion of said casing, a rectangular sheet-metal hood within said outer casing straddling the top and sides of said fire box with its top, side and rear walls spaced from the corresponding walls of said outer casing, the lower ends of the side walls of said hood terminating above the bottom wall of said outer casing, heat radiating fins on the side walls of said hood, a direct smoke flue from said fire box formed in said hood, circuitous smoke flues formed in said hood on either side of said direct flue and ported to the latter, a damper in said direct flue equipped with an operating rod extending through a wall of said outer casing, a warm air discharge flue extending through said hood and outer casing forwardly of said direct smoke flue and between said circuitous flues and communicating at its lower end with the space between said hood and fire box, and a fan mounted in the opening in the rear wall of said outer casing.

5. In a hot air furnace, the combination of a rectangular sheet-metal outer casing having a cold air supply opening in its rear wall, a fire box located in and extending full length of the lower portion of said casing, a rectangular sheet-metal hood within said outer casing straddling the top and sides of

said fire box with its top, side and rear walls spaced from the corresponding walls of said outer casing to provide downflow air passages communicating at their lower ends 5 with the interior of said hood, longitudinal and transverse partitions in said hood dividing the latter into a pair of side smoke flues, a central smoke flue communicating with said fire box, and a central warm air 10 charge flue located forwardly of said central smoke flue, said longitudinal partitions

formed with upper and lower ports through which said side and central smoke flues communicate, baffle plates in said side flues between said upper and lower ports extending 15 from the rear walls of said side flues to points near the front walls thereof, a damper in said central smoke flue between said upper and lower ports, and a fan mounted in the opening in the rear wall of said outer 20 casing.

ROBERT A. ILG.
